CALCULATING MACHINE WITH
RACK DRIVE

Cyrill Ochsner, St. Gallen, Switzerland

Application December 7, 1949, Serial No. 131,602
In Switzerland December 9, 1948

5 Claims. (Cl. 235—138)

1

My present invention relates generally to improvements in calculating machines and particularly to the transfer mechanism thereof, which mechanism is distinguished by displaceably guided toothed pawls adapted to co-operate with toothed wheels for the purpose of setting the counter wheels; the said pawls after the setting of said wheels engaging the latter for the purpose of locking same, effecting the decimal transfer, and then being rendered inoperative again.

One object of my present invention is to make provision for avoiding the risk of overrunning as exists when decimal transfer is effected directly by means of rotary members, and which risk limits the speed of operation of the machine.

Another object is to reduce the power required for actuating the traveling carriage in each denominational column.

The toothed pawls preferably are actuated in dependency on the movement of a carriage which on its forward run carries forward racks which through said toothed wheels cause the setting of the counter wheels. The said racks being rendered inoperative, are returned to their original position on the rearward run of the carriage, whereby the decimal transfer is performed through the said pawls.

The operative speed of the machine thus is still further increased by virtue of utilizing the return stroke of the carriage for effecting the decimal transfer.

One form of my present invention is shown, by way of example, in the accompanying drawing, in which—

Fig. 1 shows a longitudinal section through the machine,

Fig. 2 a top plan view thereof, the top cover plate having been removed,

Fig. 3 is a perspective view of a rack and parts co-operating therewith.

Fig. 4 shows the transfer carriage in the initial or inoperative position.

Fig. 5 shows the carriage during the return stroke, parts instrumental for decimal transfer having been actuated preparatory for such transfer.

Figs. 6 and 7 show the carriage in terminal position on completion of its forward run, without and with preparation of the decimal transfer respectively.

Figs. 8 and 9 show in two positions an end view of parts serving for engaging and disengaging the toothed pawls,

Fig. 10 is a partial vertical section in the range of a toothed pawl,

2

Fig. 11 is a section through a point of bearing of two pivotable stirrups,

Figs. 12 and 13 show two top plan views of a counter mechanism set in the additive and subtractive sense,

Figs. 14—16 show elevations with partial sections for illustrating the co-operation of an individual digit key with the stirrups shown in Fig. 11,

Figs. 17 and 18 are bottom plan views of Figs. 14 and 15, respectively,

Fig. 19 shows an elevation and section for explaining the mode of operation of an auxiliary key, and

Fig. 20 is a bottom plan view of Fig. 19.

As shown in Figs. 1 and 2, the machine frame comprises a rectangular bed plate 1 and two longitudinal wall members 2 secured thereto. The latter in top recesses accommodate a box 3 which contains the keyboard of the setting mechanism. A bonnet 1' is removably secured to the bed plate 1. In Fig. 1, a column of digit keys 4 is shown, which normally are held in inoperative position by means of springs 6 coiled about the key stems 5. In the example shown and described eight columns of digit keys 4 are provided, and a rack 7 (Fig. 2) is associated with each said column. A setting bar 8 is disposed adjacent each rack 7. All the eight setting bars 8 are interengaged with a transverse rod 9 which passes through vertical slots provided at one end of said bars. The said rod 9 is movably supported in horizontal slots 10 provided in the two longitudinal wall members 2 of the machine frame. The forked ends of two arms 11 engage said rod 9 at each end thereof, which arms are pinned to a transverse rod 12. The latter is rotatably mounted in the two frame walls 2 and at one end carries a hand crank 13 which is disposed outside the machine casing. Two further rods 14 and 15 traverse horizontal slots of the racks and setting bars 7 and 8. As shown in Figs. 1 and 3, the horizontal slots provided in the setting bars 8 for the axle 14 are open at one end of the bars. The rod 14 is secured to the two walls 2. The latter have a short vertical slot 16 each (Figs. 8, 9) for rod 15 which is mounted at its ends in an inclined slot 17 of a swing arm 18 each. The latter are pivoted on pins 19 to the wall members 2, and each arm 18 is connected to a control arm 21 by means of a connecting link 20. The arms 21 are pivoted on pins 22 to the walls 2. The rod 15 at its opposite ends is further mounted in the fork 23 of one arm of a pair of bell-crank levers 24, which latter levers are pivoted on pins 25 to the walls

2. The two bell-crank levers 24 are disposed on the insides of the walls 2, and through their second arms are interengaged by a rod 26.

The rod 26 traverses a vertical slot 27 provided at the top of vertical pawls 28, the tops of which have two teeth by means of which the pawls 28 co-act with toothed wheels 29 which engage the denominational counters and are rotatably mounted on a rod 30. When the toothed wheels 29, which are spaced from each other by means of spacing washers, are actuated through the pawls 28, decimal transfer operations are involved. A rod 32 traverses vertical slots 31 provided at the bottom of the pawls 28 and is secured to the wall members 2. Each pawl 28 is engaged by a spring 33 which at its other end is secured to a rod 34 which is fixed to the wall members 2.

Adjacent each pawl 28 there is a latching member 35 which is pivoted on and to said lower rod 32 and on its upper end possesses a laterally projecting lug 36 (see also Fig. 10). The latter co-acts with a lateral detent 37 provided on each pawl 28. To the foot of the latter, a bell-crank lever 39 is pivoted on a pin 38. One arm of the levers 39 terminates in a lug which co-acts with an auxiliary lever 40. The latter are mounted on the upper rod 34 and serve for preparing the decimal transfer. Each bell-crank lever 39 through its other arm may co-act with an arm 41. All of the latter are mounted on a common lower rod 42 and are traversed by a rod 44 through slots 43. A spring 45 for each bell-crank lever 39 is anchored on said rod 44, and the rod 42 as well as rod 44 are secured to the two wall members 2. A roller 46 is pivoted to each arm 41 and co-acts with a projection 47 provided on the lower edge of the adjacent setting bar 8. A spring 48 anchored to the rod 30 and engaging arm 41 tends to hold the latter in its upper terminal position, i. e. in the inoperative position (Figs. 4, 6, 7).

Each auxiliary lever 40 is resiliently connected to the adjacent latching member 35 by means of a spring 49. Each auxiliary lever 40 on an upper arm carries an abutment plate 50 for a set arm 51 which serves for decimal transfer and is mounted on a rod 52 which is parallel to the wheel axle 30. The rod 52 and a rod 53 parallel thereto is mounted in a rectangular casing (not shown) which is open at the bottom and belongs to the counter mechanism. The said casing is mounted on bearing pins secured to the two wall members 2 of the machine frame. The counter wheels 54 are rotatably mounted on the rod 53 and on one side each carries a toothed wheel 55 (Figs. 12, 13) which meshes with an intermediate wheel 56 rotatably mounted on the rod 52. The said casing of the counter mechanism is displaceable on its bearing pins or, respectively, in direction of the wheel rod 30, for which purpose a hand lever (not shown) is provided. The latter is selectively adjustable to a plus sign or minus sign marked on the bonnet 1'. Such arrangement permits the operator to correspondingly adjust the said casing and, thus, to couple each counter wheel 54 either directly through its lateral toothed wheel 55 or indirectly through the intermediate wheel 56 to the respective driving wheel 29, according to whether the counter wheels 54 shall be turned in the additive or subtractive sense (positions shown in Figs. 12 and 13 respectively). For the purpose of effecting the decimal transfer, a stud 57 is secured on the other side of the wheels 54,

which serves for co-acting with the respective set lever 51 mounted on rod 52.

As shown in Fig. 3, each rack 7 associated with each denominational column is provided with teeth 7a in the plane of the rack, which teeth correspond to the digit keys 1, 2, 4, 6 and 9, as shown for the respective five key stems 5. The stems 5' and 5'' of the keys corresponding to the digits 3, 5, 7 and 8 respectively, are cut out at their foot end in order to co-operate, when depressed, only with the associated tooth of rack 7. Bracketed teeth 7b on rack 7 are associated with the digits 3, 5 and 7, while a lug 7c is provided for the key of digit 8. The stem 5'' of the latter is extended to project into the path of said lug 7c when the key 4 of digit 8 is depressed.

A bail 58 and an abutment rail 59 (Figs. 15-18) are associated with each key column and through their arms 58' and 59' (Figs. 11, 14, 16) are pivoted on a rod 60 to opposite walls 3' (Fig. 1) of key box 3. A cover strip or latch 61 covers the bearing arms 58' and 59' of the elements 58 and 59 at the suspension end on the respective side of key box 3. The abutment rail 59 has a lateral lug 62 to co-operate with one of the bracketed teeth 7b of its corresponding rack 7. Springs 63 engaging the arms of the rails 59 tend to hold the latter in the inoperative position as shown in Fig. 14, in which it abuts through its bearing arms against a lateral lug 64 on each of the bails 58. The latter through the inclined surface of its web then abuts against a cross-arm of the stem 5 of the respective column of keys 4. A spring 65 engaging the bail 58 tends to hold the latter in the inoperative position, and the other end of spring 65 is secured to a bracket 66. The brackets 66 are disposed on a common trip rail 67 which is displaceably guided on the underside of key box 3 transversely of the longitudinal members 7 and 8, for which purpose elongated slots 68 provided on the trip rail 67 receive studs 69. A special key 4a (Fig. 19) disposed outside of the keyboard proper serves for actuating the trip rail 67. The key 4a by means of its stem 5a may co-operate with a bracket 66a fixed to the trip rail 67. Upon depressing the spring-loaded special key 4a, a skew surface on its stem 5a engages a lateral lug 66b of bracket 66a so as to displace the trip rail 67 from its inoperative position.

The machine shown and described operates as follows:

Having set the item in question by depressing the respective digit keys 4, the carriage which comprises the transverse rod 9 and all the setting bars 8 and which is slidable on the rods 14 and 15 traversing the longitudinal slots of the setting bars 8, is moved from its inoperative or normal terminal position (Figs. 1 and 4) into its second terminal position (Figs. 6, 7) by means of the hand crank 13 through the rod 12 and the pair of arms 11. The crank 13 is turned in direction of the arrow shown in Fig. 4 against the action of springs (not shown). The latter cause the carriage to move back into its initial or inoperative position when crank 13 is released. On depressing a key 4, the lug formed on the key stem 5 abuts against the skew surface of bail 58 so as to rock the latter laterally against spring action, the bail taking along the respective abutment rail 59 by means of its lateral lug 64. The bail 58, being biased through spring 65, then rocks back over the cross-arm of stem 5, whereupon the key 4 is secured in the depressed position. On the other hand, the abutment rail 59 is held in the

corresponding position in that it abuts through one leg of its web (which latter is angular in cross-section) against said cross-arm of key stem 5. The abutment rail 59 now is in the inoperative position in that its lug 62 is outside of the track of the respective bracketed tooth 7b of its corresponding rack 7. The racks 7 which thus have been tripped for displacement (Fig. 17), are taken along through the respective or adjacent setting bars 8 when the carriage 8, 9 runs forward, for the purpose of turning the respective toothed wheels 29 according to the numerical value to be transmitted thereonto or, respectively, on the counter wheels 54. Such transmission is defined by the contact of the respective tooth 7a, 7b or 7c with the stem 5 of the depressed key 4. The toothed wheels 29 are released through the pawls 28 when the carriage 8, 9 runs forward. According to the setting of the counter casing or, respectively, of the wheels 55 and 56, the counter wheels are turned in the additive or subtractive sense.

A leaf spring 70 secured to the underside of the adjacent setting bar 8 (Fig. 1) serves for taking along the rack 7. The spring 70 has its end rolled up to form a lobe 71 for engagement with a notch 72 provided on the lower edge of rack 7. The notch 72 is staggered relatively to a notch 73 provided on the lower edge of the associated setting bar 8. The resilient follower 70, therefore, causes rack 7 to be coupled to setting bar 8 only after the carriage 8, 9 has travelled forward through a certain distance. The notches 73 of the setting bars 8 are not staggered relatively to each other, but the followers 70 are of different lengths so that when the carriage 8, 9 runs forward, the followers 70 successively snap into the notches 72, 73 of the pairs of members 7, 8 and thus cause successive coupling between the forwardly moved setting bars 8 and the rack 7 which first are at rest. Such arrangement affords the following advantages. When starting to run the crank 13, i. e. at the beginning of the forward run of the carriage 8, 9, less power is required than afterwards when the crank has been moved. When the resilient followers 70 are disengaged, i. e. the pairs of members 7, 8 are successively uncoupled, less power is required than when all of the active followers 70 would have to be disengaged simultaneously.

In the final phase of forward run of the carriage 8, 9, the two arms 21 are rocked through rod 8 from the position shown in Fig. 8 into that shown in Fig. 9 whereby the two arms 18 are moved in the respective position through the connecting link 20. The guide rod 15 thus is moved downwardly in the vertical guide slots 16 provided in the two longitudinal frame wall members 2 through the inclined slots 17 of the two arms 18, and the two bell-crank levers 24 are rocked clockwise from the position shown in Fig. 8 into that shown in Fig. 9. By virtue of such movement, the pawls 28 are rocked through the coupling rod 26 of the two levers 24 about the lower rod 32 from the inoperative position in Fig. 4 into that shown in Fig. 5 in which they engage the toothed wheels 29 which thereby are locked in their setting position. During such engaging movement of the pawls 28, the carriage 8, 9 is rocked on the stationary guide rod 14 owing to said sinking movement of the rod 15, and the racks 7 which have been displaced from their position of rest are disengaged from the toothed wheels 29.

After the carriage 8, 9 has performed its full stroke, the handle 13 is released, whereupon the carriage is rapidly returned through the action

of said springs into its initial position, the racks 7 (which had been taken along by the carriage on its forward movement) being restored into their inactive position. The handle 13 which 5 swings back into its initial position during the rearward run of the carriage 8, 9, subsequently is turned again against spring action to initiate another forward run of carriage 8, 9, after the depressed keys 4 have been returned again into 10 their inactive position (in a manner set out hereinafter) and after a second numerical value has been set in the setting mechanism by means of the keys 4.

The backward run of carriage 8, 9 is utilized 15 in the following manner for carrying out the decimal transfer.

The arms 41 against the action of the springs 48 are temporarily rocked downwardly about the rod 42 from the position shown in Figs. 4, 6 and 20 7 into that shown in Fig. 5, by virtue of a temporary co-operation of the cams 47 on the setting bars 8 with the rollers 46 pivoted to the arms 41. Such rocking movement has no effect 25 on the pawls 28 of those toothed wheels 29 and, thus, of those counter wheels 54 for which no decimal transfer is contemplated. Decimal transfer will take place, however, at the points where preparation has been made therefor by the lateral stud 57 on the counter wheels 54. For such 30 preparatory purpose, the respective adjusting lever 51 has been rocked through said stud 57 so as to rock the auxiliary lever 40 through the abutment plate 50 against the action of spring 33 clockwise, i. e. from the position shown in Fig. 35 6 into that shown in Fig. 7. During such rocking movement, the auxiliary lever 40 has tripped the abutment lever 39 which thus is rocked through spring 45 and, as shown in Fig. 7, abuts against the foot of pawl 28. When the arm 41 subsequently is rocked downwardly by the bottom cam 47 of setting bar 8, the latter engages the abutment lever 39 which is pivoted to pawl 28 whereby the latter is downwardly displaced with respect to the two rods 26 and 32 for an amount corresponding 45 to one tooth spacing, which displacement causes the respective counter wheel 54 to be rocked through an angle corresponding to one unit or division.

In order to ensure a positive transmission of 50 such decimal transfer from counter wheel to counter wheel (from the tens to the hundreds, from the latter to the thousands, and so on), the bottom cams 47 of the setting bars 8 are staggered relatively to each other. When the pawl 55 28 is depressed, as stated above, its lateral catch 37 (Fig. 10) slides along the lug 36 of the latching member 35 and leaves the same below, whereupon the member 35 is rocked through the springs 49 so as to abut against the bearing rod 60 34 of the auxiliary lever 40. The lateral lug 36 of the latching member 35 now is situated directly above the top end face of said catch 37, and the pawl 28 thus is secured against upward displacement. In the final phase of the backward run of carriage 8, 9 the cross-rod 9 abuts 65 against the swing arms 18 which thus are rocked back into their normal position, and the rod 15 also is turned back into its inactive position by means of the slots 17 and 16 in said arm 18 and 70 in the two longitudinal wall members 2. The carriage 8, 9 thus is correspondingly rocked on the rod 15 so as to assume its initial position again, in which the racks 7 with their respective terminal teeth are engaged to the toothed wheels 75 29. The toothed wheels 29 and counter wheels

54 thus are locked in their setting position. On the other hand, the two bell-crank levers 24 are rocked through the rod 15 (when the latter turns back into the inactive position) so that the pawls 28 are disengaged from the toothed wheels 29 by means of the coupling rod 26. The lateral catch 37 of pawl 28 in Fig. 5 is moved to the left out of range of the upper lug 36 on arm 35 i. e. the pawl 28 is released and through spring 33 moved axially upward on the two rods 26, 32 into its initial or inactive position (Fig. 4).

In order to restore the keys 4 to their inactive position, the tripping rail 57 is displaced from its position of rest by means of the auxiliary key 4a (Fig. 19), the bails 58 (which have become active on setting an item by means of the key 4) are rocked through the angled holders 66 so as to become inactive. When released, the key 4a moves back to its inactive position. When depressing the auxiliary key 4a, a latch 58a engages an abutment stirrup 59a and is rocked therewith in corresponding manner, for which purpose the key stem 5a co-acts with a lug 66b provided on holder 66a which latter is subjected to the action of a spring 55a (Fig. 20). The two stirrups 58a and 59a are destined for further functions for which no further details are shown here. The stirrup 59a is secured in the rocked position by means of a rod 5b (Figs. 19, 20) of a second auxiliary key.

What I claim as new and desire to secure by Letters Patent is:

1. In a decimal transfer mechanism, a traveling carriage for each denominational column, a rack associated with said carriage and adapted to be engaged by the latter on the forward run thereof, counter wheels, toothed wheels for driving said counter wheels, a plurality of displaceably guided tooth pawls adapted to engage and lock the toothed wheels after setting of the counter wheels by said racks, means cooperating between said racks and pawls for actuating the said pawls in dependency on the movement of said carriage or carriages, the said rack or racks being adapted to set the counter wheels through the toothed wheels on the forward run of the racks and to be taken along on the backward run of the carriage in inactive position, abutment levers pivoted on said pawls, means normally maintaining said abutment levers in an inactive position in the absence of a decimal transfer, means operating between said counter wheels and said last named means for operating the latter to permit said abutment levers to move to active position to effect a decimal transfer, and means cooperating between said abutment levers to effect the decimal transfer during the backward run of said carriages.

2. In a decimal transfer mechanism as set out

in claim 1, the plurality of traveling carriages being slidably mounted on two guide rods disposed at right angles across the entire width of the machine, operating means connected with the carriage for sliding the same relative to said rods, and linkage means cooperating with one of said rods and said operating means for lowering and raising the said one rod in the final phase of the forward run and backward run respectively of the carriage, whereby the carriage is tilted on the other of said rods and the racks with respect to the appurtenant toothed wheels are disengaged and engaged respectively.

3. In a decimal transfer mechanism as set out in claim 2, the plurality of carriages each comprising a setting bar set on edge and a resilient follower, said follower for each setting bar being each of a different length thereby to successively pick up and take along its associated rack during the forward run of the carriage as far as the racks are used for carrying out the calculating operation.

4. In a decimal transfer mechanism as set out in claim 3, a cross-rod engaging all the said carriages to initiate the raising and lowering of the respective guide rod, linkage means associated with the latter and said pawls whereby said pawls are engaged and disengaged with respect to the appurtenant toothed wheels, and means on the setting bars of said carriages for causing movement of the pawls for decimal transfer.

5. In a decimal transfer mechanism as set out in claim 4, the toothed pawls displaceably guided on two parallel rods, one of the latter being adapted to tilt the pawls for engaging and disengaging, and securing arms associated with said pawls and pivotably mounted on the second rod for co-acting with said pawls to secure same in position on completion of the movement for decimal transfer until the pawls are again disengaged.

CYRILL OCHSNER.
